(57) **CLAIM**

The ornamental design for a display screen or portion thereof with animated graphical user interface, as shown and described.

DESCRIPTION

FIG. 1 is a front view of a display screen or portion thereof with animated graphical user interface showing a first image of our new design;

FIG. 2 is a second image thereof;

FIG. 3 is a third image thereof;

FIG. 4 is a front view of an electronic device on which the display screen with animated graphical user interface may be displayed;

FIG. 5 is a rear view thereof;

FIG. 6 is top view thereof;

FIG. 7 is a bottom view thereof;

FIG. 8 is a left view thereof; and,

FIG. 9 is a right view thereof.

The appearance of the animated images sequentially transitions between the images shown in FIGS. 1 through 3. The process or period in which one image transitions to another forms no part of the claimed design.

The outermost broken lines in the Figures show a display screen or portion thereof, and form no part of the claimed design. The other broken lines in the Figures show portion of the animated graphical user interface that form no part of the claimed design.
